DESIGN FOR A PHOTOCOPYING APPARATUS

Abe J. Greenblau, Chicago, Ill.

Application February 14, 1940, Serial No. 90,251

Term of patent 7 years

To all whom it may concern:

Be it known that I, Abe J. Greenblau, a citizen of the United States, residing at Chicago, in the county of Cook and State of Illinois, have invented a new, original, and ornamental Design for a Photocopying Apparatus, of which the following is a specification, reference being had to the accompanying drawing, forming a part thereof.

In the drawing:

I claim:

The ornamental design for a photocopying apparatus, substantially as shown.

ABE J. GREENBLAU.
